ELECTRICAL IGNITION APPARATUS

Filed Aug. 30, 1940

FIG. 1.

FIG. 2.

Inventor: **FRED MIESS**
by: **John E. Jackson** This Attorney.

UNITED STATES PATENT OFFICE

2,299,642

ELECTRICAL IGNITION APPARATUS

Fred Miess, Gary, Ind.

Application August 30, 1940, Serial No. 354,887

5 Claims. (Cl. 175—373)

This invention relates to electrical ignition apparatus, and more particularly to those which are used in connection with the fuel nozzles of an industrial furnace, although not limited thereto. Such apparatus supply strong electrical impulses of short duration.

One of the objects of the present invention is that it provides very effective ignition with a very low electrical power consumption.

Another object is to provide a simple, rugged, reliable and sparkless means of rapidly and alternately closing and opening a charging circuit and a discharging circuit.

The foregoing and other objects will be apparent from the following specification and the drawing, in which:

Figure 1 is a diagram illustrating in section certain details of construction; and

Figure 2 is a sectional view on the line II—II of Figure 1.

As pointed out in my co-pending application, Serial No. 245,765, filed December 14, 1938, ignition apparatus now in general use is of two main types. One is the make-and-break type found in automobile or other internal combustion engine ignition systems, where a primary circuit of a step-up transformer is opened and closed to effect periodic generation of energy in the secondary of the transformer. The other is the type more generally found in industrial applications, and consists of a step-up transformer directly connected to an alternating current line, so that there is a continuous arcing across the ignition points. This latter type makes a very simple, rugged and reliable ignition system especially adapted to the supplying simultaneously of ignition impulses to a large number of gaps or pairs of points. This type, for example, is generally found on industrial furnaces having large numbers of fuel jets or burners as, for example, annealing furnaces in the steel industry. For reasons concerned with safety, such ignition apparatus is generally run continuously while fluid fuel is being supplied to the furnace; and this results in one of the principal objectionable features of such a system, a large energy consumption.

The present invention is fundamentally similar to that of my co-pending application, Serial No. 245,765, but provides a more rugged and simple apparatus with greater capacity.

Referring more particularly to the drawing, the numeral 10 designates a motor which is suitably connected to a shaft 11, the latter in turn being journaled in a pair of spaced aligned bearings 12

whereby it is suitably mounted for rotation at a given desired speed. Disposed intermediate the bearings 12, the shaft 11 carries a pair of spaced collector rings 14 and 15. Disposed between the collector rings 14 and 15, the shaft 11 carries a hub 20 to which there is suitably connected a disk 22 of electrical insulating material and which carries on its periphery a pair of opposed electrical contact segments 23 and 24. The disk 22 is composed of any suitable electrical insulating material whereby the contact segments 23 and 24 are maintained electrically insulated from said shaft and also from each other.

The collector ring 14 on the shaft 11 is electrically connected to the contact segment 23 by means of a wire 26, while the collector ring 15 is connected to the contact segment 24 by a wire 27.

Disposed beneath the shaft 11 and in a position facing the contact segments 23 and 24 is a mercury well 30 which is provided with a spout 31 so constructed and arranged as to project mercury onto the said contact segments when they occupy the lowermost position in their periods of rotation with the shaft 11. Mercury is supplied to the mercury well 30 through a feed line 33 which is connected with a suitable mercury pump 35, the latter preferably being of that type which is described and claimed in my co-pending application, entitled "Centrifugal pump," filed August 27, 1940, and bearing Serial No. 354,432.

Disposed immediately below the disk 22 which carries the contact segments 23 and 24 there is provided a well 37 which receives the mercury after it has been projected onto the said segments. From the well 37 the mercury passes through an aperture 38, tube 39, and back into the mercury circulating system which comprises the mercury pump 35.

The stream of mercury, designated at X, is projected onto the segments 23 and 24 as they occupy their lowermost positions and will be cut thereby for the purposes of breaking a circuit and accomplishing results which will appear more fully hereinafter.

In Figure 1, the numerals 40 and 41 designate power lines connected to a suitable source of direct current. The line 40 is connected through a double pole single throw switch 43 to a line 45 which is connected in series to an electrical "check-valve" 47 (i. e., "Tungar" bulb or the like), inductance 48, resistance 49, and then to a collector ring brush 50 which makes contact with the collector ring 14. Referring to the lower

left-hand portion of Figure 1, the line 41 is connected through the double pole single throw switch 43 with a line 55 which connects with the former of a pair of power lines 56 and 57 through the medium of a double pole single throw switch 58. The line 57 is connected through the double pole single throw switch 58 with a line 60. The line 60 is connected to a collector ring brush 61 which makes contact with the collector ring 15. Across the lines 60 and 55 (which are the output wires) there is disposed a permanently connected load 63 which is just ahead of the switch 58 (which is the output switch). With a very light load the contact between the segment 24 and the mercury stream might separate before condenser 66 were completely discharged, that is, while current still flowed in the discharge circuit. Under this condition, sparking would occur at the point of separation of the contact. The permanently connected load 63 is so constructed and arranged as to discharge the condenser 66 in the allotted time even with no load connected to the lines 56 and 57. Through the output switch 58 impulses are fed to a two-wire distribution circuit comprising the lines 56 and 57.

Between the switch 43 and the permanently connected load 63 the line 55 is connected with the mercury well 30 by means of a line 65 in which there is disposed an electrical condenser 66 of considerable capacitance.

In operation:

With the shaft 11 in the position shown in Figure 1, one side of the condenser 66 is connected through the lines 65 and 55 and the switch 43 to the line 41 of the direct current source. The other side of the condenser 66 is connected through the line 65, mercury stream X, segment 23, wire 26, collector ring 14, collector ring brush 50, resistance 49, inductance 48, electrical "check-valve" 47, line 45 and switch 43 to the line 40 of the direct current source. Thus the condenser 66 receives a charge during the time that the segment 23 is in contact with the mercury stream X. A little later, in the revolution of the shaft 11, this contact is broken and the charging circuit is opened.

A little later in the revolution of the shaft 11, the segment 24 makes contact with the mercury stream X, establishing a circuit from the condenser 66 through the line 65, mercury stream X, segment 24, wire 27, collector ring 15, collector ring brush 61, line 60 and switch 58 to the line 57 of the discharge circuit. The other side of the condenser 66 is already connected through the line 65, line 55 and switch 58 to the line 56 of the discharge circuit. Thus the condenser 66 discharges its stored energy into the lines 56 and 57 and partly or wholly into the permanently connected load 63, depending on the amount of load connected to the said lines.

Still a little later, in the revolution of the shaft 11, contact between the segment 24 and the mercury stream X is broken, thus opening the discharge circuit, after which the charging circuit is again closed and the cycle repeated indefinitely.

The provision of the inductance 48 and the resistance 49 accomplishes two highly desirable results. By the proper proportion of the inductance 48 to the capacitance of the condenser 66, the charging circuit may be "tuned" to bring the charging current to zero value at the instant that the charging circuit is to be opened, thus securing sparkless operation of the circuit.

By properly proportioning the resistance 49 of the "tuned" charging circuit, it may be given any desired decrement and thus permit of the charging of the condenser 66 to a voltage which is either equal to or higher or lower than the voltage of the charging source. This eliminates the necessity of a motor generator or other source of special voltage as a charging source; and will permit the use of a standard 250 volt direct current house circuit as a charging source. The "tuning" can be done very accurately in the case of a direct current circuit of steady voltage, and steady speed of the switching means. A fluctuating voltage or speed of the switching means might introduce some discrepancies; and in order to eliminate this possibility, there has been included in the charging circuit the electrical "check-valve" 47 in the form of the "Tungar" bulb. This electrical "check-valve" is not used as an ordinary rectifier to supply direct current from an alternating current source, but is used in connection with the "tuned" charging circuit to hold the current at zero value until the charging circuit has been opened by the switching means. In other words, the "tuned" circuit brings the charging current to zero value at the desired time; and the "check-valve" holds the current at zero value until the charging circuit is opened. This period might extend over any number of oscillation cycles and the current still remain continuously at zero value. This, obviously, is not true of ordinary rectification where the current would be at zero value only during every other half cycle.

While I have shown and described one specific embodiment of the present invention, it will be seen that I do not wish to be limited exactly thereto, since various modifications may be made without departing from the scope of the invention, as defined by the following claims.

I claim:

1. Apparatus of the character described for periodically supplying a strong electrical impulse of short duration from a source of electrical energy, including: a condenser; a source of current adapted to charge said condenser; an inductance in the charging circuit of said condenser, said inductance being so proportioned with respect to the capacitance of said condenser as to provide a tuned charging circuit; and means for periodically disconnecting said condenser from said source and connecting it to the circuit to which said strong impulse is to be delivered.

2. Apparatus of the character described for periodically supplying a strong electrical impulse of short duration from a source of electrical energy, including: a condenser; a source of current adapted to charge said condenser; an inductance in the charging circuit of said condenser, said inductance being so proportioned with respect to the capacitance of said condenser as to provide a tuned charging circuit; a resistance in the charging circuit of said condenser, said resistance being proportioned with respect to said inductance and the capacitance of said condenser to give the desired decrement to condenser voltage oscillation; and means for periodically disconnecting said condenser from said source and connecting it to the circuit to which said strong impulse is to be delivered.

3. Apparatus of the character described for periodically supplying a strong electrical impulse of short duration from a source of electrical energy, including: a condenser; a source of cur-

rent adapted to charge said condenser; an inductance in the charging circuit of said condenser, said inductance being so proportioned with respect to the capacitance of said condenser as to provide a tuned charging circuit; an electrical check valve in the charging circuit of said condenser; and means for periodically disconnecting said condenser from said source and connecting it to the circuit to which said strong impulse is to be delivered.

4. Apparatus of the character described for periodically supplying a strong electrical impulse of short duration from a source of electrical energy, including: a condenser; a source of current adapted to charge said condenser; an inductance in the charging circuit of said condenser, said inductance being so proportioned with respect to the capacitance of said condenser as to provide a tuned charging circuit; a resistance in the charging circuit of said condenser, said resistance being proportioned with respect to said inductance and the capacitance of said condenser to give the desired decrement to condenser voltage oscillation; an electrical check valve in the charging circuit of said condenser; and means for periodically disconnecting

said condenser from said source and connecting it to the circuit to which said strong impulse is to be delivered.

5. Apparatus of the character described for periodically supplying a strong electrical impulse of short duration from a source of electrical energy, including: a condenser; a source of current adapted to charge said condenser; an inductance in the charging circuit of said condenser, said inductance being so proportioned with respect to the capacitance of said condenser as to provide a tuned charging circuit; a resistance in the charging circuit of said condenser, said resistance being proportioned with respect to said inductance and the capacitance of said condenser to give the desired decrement to condenser voltage oscillation; an electrical check valve in the charging circuit of said condenser; a permanently connected load across the discharge circuit of said condenser; and means for periodically disconnecting said condenser from said source and connecting it to the circuit to which said strong impulse is to be delivered.
